UNITED STATES PATENT OFFICE.

CHARLES A. SULZMAN, OF WATERFORD, NEW YORK.

STEAM-TRAP.

SPECIFICATION forming part of Letters Patent No. 444,214, dated January 6, 1891.

Application filed May 27, 1889. Serial No. 312,250. (No model.)

To all whom it may concern:

Be it known that I, CHARLES A. SULZMAN, a resident of Waterford, in the county of Saratoga and State of New York, have invented 5 certain new and useful Improvements in Steam-Traps; and I do hereby declare that the following is a full, clear, and exact description of the invention, that will enable others skilled in the art to which it appertains to 10 make and use the same, reference being had to the accompanying drawings, and to the letters of reference marked thereon, which form a part of this specification.

Similar letters refer to similar parts in the 15 several figures therein.

My invention relates to improvements in steam-traps; and it consists of the novel construction and combination of parts hereinafter described and subsequently claimed.

20 Figure 1 of the drawings is a central vertical section taken on the broken line 1 1 in Fig. 2, showing the live-steam connections and the controlling-spring in elevation. Fig. 2 is a horizontal section taken on the line 2 2 in Fig. 1. Fig. 3 is a plan view of the three-chambered cylinder detached. Fig. 4 is a central longitudinal section of the same, taken on the broken line 4 4 in Fig. 3. Fig. 5 is a 25 cross-sectional view of the chambered cylinder and valve-case, taken on the broken line 5 5 in Fig. 2. Fig. 6 is a view similar to that shown in Fig. 5, taken on the broken line 6 6 in Fig. 2.

A A' are two tanks or reservoirs, each supported by a steam-pipe A² and a water-pipe A³, by which they are connected with a valve-case B. The valve-case is in turn supported by a three-chambered cylinder C, upon which it is fitted to rock and open and close ports 30 between the cylinder-chambers and the valve-case chambers. One of the end chambers R in the cylinder is adapted to receive the water of condensation through pipe R', screwed therein, and the other end chamber D to receive from the tanks and discharge such water to the boiler, located upon a lower level, and not shown, through discharge-pipe D' screwed therein. The central cylinder-chamber S is a steam-chamber adapted to receive 35 live steam direct from the boiler through steam-pipe S'. (Shown broken away in Fig. 1.) The valve-case is provided with four

chambers, two on each side—namely, the water-chamber B', connected with tank A' at its lower end by a water-pipe A³, and the steam-chamber B², connected with the tank A' at its upper end by a steam-pipe A², and on the other side a similar water-chamber B³ and steam-chamber B⁴, connected in similar manner with tank A, as shown in Fig. 2. 60

The contiguous portions of the cylinder-shell and the valve-case are provided with ports connecting the several chambers, as follows: Ports C' and C² connect chambers D and B', and are shown open in Fig. 5, as well 65 as in the other figures. Ports C³ and C⁴ (also shown open) connect chambers R and B³. Ports C⁵ and C⁶ (shown closed) when open connect chambers D and B³, and ports C⁷ and C⁸ (shown closed) when open connect chambers 70 R and B'. Ports C⁹ and C¹⁰ (shown open) connect chambers S and B², and ports C¹² and C¹³ (shown closed) when open connect chambers S and B⁴. The top of the valve-case may be cast integral with the case or in a separate 75 detachable plate, as indicated by dotted lines in Fig. 1.

The cylinder is supported in a fixed position, as by its end pipes and steam-pipe S', and the valve-case is secured to the cylinder 80 by end clips B⁵ passing around the cylinder and secured to the case, as by screws B⁶. The cylinder is also provided with a small groove C¹⁴ in its periphery, extending part way only around the cylinder between the ports C⁹ and 85 C¹² and in line therewith, and consequently in line with the ports C¹⁰ and C¹³, and adapted to alternately communicate with each. The case is also provided with a duct or passage-way leading from the groove in the cylinder 90 through the partition to the atmosphere, as shown in Fig. 1. It will thus be seen that when the ports C⁹ and C¹⁰ are open port C¹⁰ is closed to the groove C¹⁴ and open to C¹³, and when the valve-case rocks sufficiently to 95 open ports C¹² and C¹³ the port C¹³ is closed to the groove and port C¹⁰ open to it and closed to port C⁹, thereby affording an atmospheric vent for the tanks through the steam-pipes A² when such pipes are cut off from communication with the steam-pipe S' leading to the 100 boiler.

The rocking movements of the tanks and valve-case are controlled by the weight of the

tanks and contents and the spring D⁶, having the hooked ends D⁴, and secured to a fixed support D², as by screws D³. The hooks are adapted to engage with the inclined ledges A⁴ on the outer sides of the tanks. When preferred, a weight W (shown by dotted lines in Fig. 1) may be employed in place of the spring to assist in controlling the rocking movements.

10 The operation of the device is as follows: As seen in Fig. 1, the tanks are about half-full of water, as indicated by the dotted lines A⁵, the lower tank A' is being discharged, and the upper tank A is being filled by the water of condensation, which enters by gravity from a higher level (not shown) or by pressure through pipe R', chamber R, open ports C³ and C⁴, chamber B³, and pipe A³, the steam-ports C¹² and C¹³ and discharge-ports C⁵ and C⁶ being closed, and the air inclosed within the tank escaping through the pipe A², chamber B⁴, port C¹¹, groove C¹⁴, and duct C¹⁵. Meanwhile the water in the lower tank has been discharged by gravity to the boiler on a lower level through pipe A³, chamber B', ports C² and C', chamber D, and pipe D', live steam from the boiler to equalize the pressure having been admitted through pipe A², chamber B², ports C⁹ and C¹⁰, chamber S, and steam-pipe S', the water in the lower part of the tank being forced out on the principle of the siphon. The resilient force of the spring D⁶ is so graduated that when the upper tank is filled or nearly filled and the lower one emptied the weight of the filled tank overcomes such force and the hooked end D⁴ slips off the inclined ledge A⁴, whereupon the filled tank falls with sufficient force upon the other end of the spring to push its ledge A⁴ beneath the hook, securing the tank A in a position similar to the position of A', as shown in the drawings, the latter tank assuming the elevated position previously occupied by the other tank. It is obvious, also, that such a movement of the tanks and valve-case opens the ports which were previously closed and closes those which were previously open. Steam is therefore admitted to the filled tank, which establishes a balanced boiler-pressure therein, and the top of the tank being on a higher level than the highest part of the discharge-pipe A³ the water commences to flow from the tank to the boiler by force of gravity alone, which flow is continued by atmospheric pressure on well-known siphonic principles until the tank is emptied or until it is released from the spring by the weight of the other tank, which

has meanwhile been filling with water of condensation through pipe R', chamber R, ports C⁷ and C⁸, chamber B', and pipe A², steam-ports C⁹ and C¹⁰ and discharge-ports C' and C² being closed and port C¹⁰ being open through groove C¹⁴ and duct C¹⁵ to the atmosphere. A rocking movement of the valve-case is thus automatically maintained to operate the various ports and cause the water of condensation to flow by gravity back into the boiler.

It will be observed that no hinged or drop valves are employed, the ports all being closed by slide-valves, which are not likely to get out of order, and are not only durable, but can be easily and cheaply constructed.

What I claim as new, and desire to secure by Letters Patent, is—

1. In a steam-trap, a fixed cylinder having a water-receiving chamber and eduction-ports at one end, a water-receiving chamber and induction-ports at the other end, and a central steam-chamber and eduction-ports, in combination with a water-supply pipe, a water-discharge pipe, a steam-supply pipe, a valve-case having one side concaved to fit such cylinder, substantially as described, and provided with water and steam chambers and ports leading therefrom adapted to alternately register with the cylinder-ports, substantially as described, two oppositely-located water-tanks supported by the valve-case, a steam-pipe connecting the upper end of each tank with a steam-chamber in the valve-case, a water-pipe connecting the lower end of each tank with a water-chamber in the valve-case, and means for controlling the rocking movements of the valve-case, as spring D⁶ and engaging ledges A⁴ upon the tanks, substantially as described.

2. In a water-trap having a pair of oppositely-located water-tanks supported by a valve-case adapted to rock upon a chambered cylinder, each connected with the case by a live-steam pipe, valved air-vents consisting of a duct C¹⁵ in the valve-case leading to a groove C¹⁴ in the periphery of the cylinder, valved ports C¹⁰ and C¹³, adapted to alternately register with such groove, and steam-pipe A², substantially as described.

In testimony whereof I have hereunto set my hand this 18th day of May, 1889.

CHARLES A. SULZMAN.
